US0D1001753S

(12) **United States Design Patent** (10) **Patent No.:** **US D1,001,753 S**
(45) **Date of Patent:** **** Oct. 17, 2023**

(54) **CIRCUIT BOARD**

(71) Applicant: **THE NOCO COMPANY**, Glenwillow, OH (US)

(72) Inventors: **James P. McBride**, Phoenix, AZ (US); **Matthew Michael Bosway**, Gilbert, AZ (US)

(73) Assignee: **THE NOCO COMPANY**, Glenwillow, OH (US)

(**) Term: **15 Years**

(21) Appl. No.: **29/864,766**

(22) Filed: **Jun. 17, 2022**

Related U.S. Application Data

(63) Continuation of application No. 29/704,997, filed on Sep. 9, 2019, now Pat. No. Des. 958,762, which is a continuation of application No. 16/564,758, filed on Sep. 9, 2019, now Pat. No. 11,251,507.

(57) **CLAIM**

The ornamental design for a circuit board, as shown and described.

DESCRIPTION

The sole FIGURE is a front elevational view of a circuit board, showing our new design.

The broken lines shown in the drawings depict environmental structure or portions of the article that form no part of the claimed design.

All surfaces not shown form no part of the claimed design.

1 Claim, 1 Drawing Sheet
